UNITED STATES PATENT OFFICE.

WILLIAM C. FREE, OF ROCKFORD, ILLINOIS.

DESIGN FOR A SEWING-MACHINE CABINET.

52,874.

Specification for Design.

Patented Jan. 14, 1919.

Application filed November 18, 1918. Serial No. 263,086. Term of patent 14 years.

To all whom it may concern:

Be it known that I, WILLIAM C. FREE, a citizen of the United States, residing at Rockford, in the county of Winnebago and State of Illinois, have invented a new, original, and ornamental Design for Sewing-Machine Cabinets, of which the following is a specification, reference being had to

the accompanying drawing, forming part thereof.

The figure is a perspective view of a sewing machine cabinet, showing my new design.

I claim:

The ornamental design for a sewing machine cabinet, as shown.

WILLIAM C. FREE.
